UNITED STATES PATENT OFFICE.

BANCROFT G. BRAINE, OF NEW YORK, N. Y., ASSIGNOR TO THE RAIL JOINT COMPANY, OF NEW YORK, N. Y., A CORPORATION OF NEW YORK.

RAIL-JOINT.

No. 927,105.

Specification of Letters Patent.

Patented July 6, 1909.

Application filed February 21, 1908. Serial No. 417,115.

To all whom it may concern:

Be it known that I, BANCROFT G. BRAINE, a citizen of the United States, residing at New York city, in the county of New York and State of New York, have invented certain new and useful Improvements in Rail-Joints, of which the following is a specification.

This invention relates to the subject of rail joints, and more particularly to that general type of joints known as the continuous rail joint.

The standard type of continuous rail joint is characterized by the employment of joint bars, each of which is rolled to provide an upright member or girder interposed between the rail head and the upper side of the rail flange, an outwardly extending foot flange overlying the base flange of the rail, and an inwardly extending rail supporting base section integrated with the outer edge of the foot flange and underlying and bearing against the rail base. Experience has shown that it is difficult to secure absolute uniformity in the rolling of the rails and joint bars of the type described so as to insure a perfect fit of the joint bar to the base flange of the rail, inasmuch as the height of the rails between the under side of the head and the outer side of the base flange, frequently varies to such an extent that a perfect fit is not obtained when the joint bars are drawn on to the rails.

It is, therefore, the distinctive object of the present invention to provide an improvement in the construction of joint bars of the continuous type so as to insure a perfect, though firm, fit for the joint bars under the rail head and on top of the base flanges of the rails, while at the same time preserving all of the desirable features of the continuous type of rail joint.

More specifically, the invention has in view a modification in the end portions of the joint bars overlying the ties whereby such a degree of flexibility is provided for in these end portions of the joint bars as to insure a perfect fit to the joint, while at the same time not gripping the flange of the rail quite so tight as is the case with the conventional designs.

The invention also has in view a construction equally serviceable as a standard joint, or in connection with an insulating joint.

With these and many other objects in view, which will readily appear as the nature of the invention is better understood, the same consists in the novel construction, combination, and arrangement of parts herein-after more fully described, illustrated and claimed.

The essential features of the invention involved in carrying out the objects above indicated are necessarily susceptible to numerous variations by way of structural modification, without departing from the scope of the invention, but certain practical embodiments thereof are exemplified by the accompanying drawings, in which:

Figure 1 is a side elevation of a rail joint embodying joint bars of the continuous type and constructed in accordance with the present invention. Fig. 2 is a cross sectional view of the joint on the line 2—2 of Fig. 1. Fig. 3 is a similar view on the line 3—3 of Fig. 1.

Like references designate corresponding parts in the several figures of the drawings.

As indicated, the invention claimed herein possesses special utility in connection with the continuous type of rail joint, and as shown in the drawings, a joint of this character includes in its construction the service rails R, the usual joint bolts 1, and the oppositely arranged continuous joint bars 2. Each of the continuous joint bars 2 is rolled into an angle bar formation, the same consisting of an upright member or splice bar portion 3 formed at its upper edge with a thickened bearing head 4 engaging against the underside of the rail head, and at its lower edge formed with an outwardly extending foot flange 5 overlying the base flanges of the rails, and having integrated with the outer edge portion thereof an inwardly extending rail supporting base section 6 underlying and bearing against the rail base. This structure provides, between the flange 5 and the base section 6, a flange receiving pocket or space 7 for the reception of the base flanges of the rails.

The several elements above indicated are characteristic of the continuous type of joint bar, and the essential functions thereof are fully preserved by the present invention, but a distinctive feature of the latter resides in providing each joint bar in the end portions thereof with what may be characterized as longitudinally disposed easing open-

ings 8. These easing openings 8 pierce each end portion of the joint bar and extend back from the ends or extremities of the bar to approximately the edge of the tie, and in the practical construction of the joint bar it is preferable that each easing opening 8 occupy approximately one-third of the length of the bar, although this proportion is not essential and may be varied without affecting the scope of the invention.

It will be observed that the easing openings 8 are formed in the angle bar member of the joint bar at the outer edge of the foot flange thereof, and therefore separate, by a well defined opening, space, or slit, the said edge portion of the angle bar from the adjacent edge portion of the base plate 6, as is plainly shown in both Figs. 1 and 3 of the drawings. In other words, the easing openings 8 pierce the end portions of the joint bar in the plane of the juncture between the foot flange 5 and the base section 6, and thus serve to separate said flange from the base plate at the end portions of the joint overlying the ties. By reason of this arrangement of the easing openings 8, it will be obvious that a perfect fit of the bars to the rails is provided for on account of the relative flexibility permitted between the end portions of the joint bars and the base sections 6, which flexibility insures perfect engagement and fit of the parts. In this connection it will be further observed that this feature of the invention is of special advantage, particularly in view of the fact that the rails often vary in their dimensions, and when the flanges of the rail are thick or thin, the flexible end portions of the joint bar will, in every case, give the necessary and proper bearing to the base of the rail. Furthermore, it will be noted that the construction described provides definite and positive means whereby the joint bars do not grip the flanges of the rail as tightly as in the conventional types of continuous bars now in use.

Any practical method of providing the easing openings 8 in the joint bars may be resorted to, but a practical expedient is suggested in the drawings, viz: that of slitting the bars along the line of cut designated by the reference number 9 at a suitable stage in the process of rolling the bars, and then upsetting the metal from the slit to not only open up the spaces or openings 8, but also to provide the spiking flanges 10 lying in the plane of the base section 6 at the outer edges thereof. However, these details may be changed or varied according to manufacturing requirements or as good practice may demand without affecting the invention.

In the drawings the intermediate portions of the joint bars between the slotted end portions are shown as preserving the conventional design illustrated in Fig. 2 of the drawings, and in which the base sections 6

are continued directly from the foot flanges 5, but it will also be understood in this connection that any variation desired in this part of the joint may also be resorted to without affecting the functions of the slotted end portions referred to. Furthermore, the construction described is not only valuable for use in connection with standard joints, but is equally available for use in connection with joints of the insulated type.

From the foregoing, it is thought that the construction, operation, and many advantages of the herein described improvement in rail joints may be readily apparent without further description, and it will also be understood that various changes in the form, proportion, and minor details of construction may be resorted to without departing from the spirit or sacrificing any of the advantages of the invention.

I claim:

1. A rail joint bar having a splice bar portion, a rail-supporting base section integral therewith, and an easing opening piercing the body of the bar in a plane above the base section.

2. A rail joint bar having a splice bar portion, a rail-supporting base section integral with said splice bar portion, and a longitudinally arranged easing opening piercing the joint bar adjacent to and above one edge of the base section.

3. A one-piece rail joint bar comprising an angle bar member and a base section, and having an easing opening piercing the angle bar member adjacent to the base section.

4. A one-piece rail joint bar comprising an angle bar member and a base section, and provided with a longitudinal easing opening piercing the angle bar member adjacent to the base section.

5. A one-piece rail joint bar comprising an angle bar member and a base section, and provided in the opposite end portions of its foot flange with easing openings.

6. A one-piece rail joint bar comprising an angle bar member and a base section, and provided in the opposite end portions of its foot flange with longitudinal easing openings.

7. A one-piece rail joint bar comprising an angle bar member and a base section, and provided in opposite end portions of its foot flange with longitudinal easing openings separating the foot flange from the adjacent edges of the base section.

8. A one-piece rail joint bar comprising an angle bar member and a base section, and provided in opposite end portions of its foot flange with easing openings disposed longitudinally and extending inwardly from the ends of the bar, said openings separating the outer edges of the foot flange from the adjacent edge of the base section.

9. A one-piece rail joint bar comprising an angle bar member and a base section, and

provided with easing openings between the foot flange and base section and spiking flanges within the plane of said openings.

10. A one-piece rail joint bar comprising an angle bar member and a base section, and slitted in its end portions between the base section and the foot flange of the angle bar.

11. A one-piece rail joint bar comprising an angle bar member and a base section, and slitted at its opposite end portions between the base section and the foot flange of the angle bar, the metal at one side of the slit being turned out to form spiking flanges.

12. A rail joint bar having an integral base section, and an easing opening piercing the 15 bar body toward the ends thereof.

13. A rail joint bar having an integral base section, and a longitudinal easing opening piercing the bar body toward the ends thereof.

In testimony whereof I hereunto affix my signature in the presence of two witnesses.

BANCROFT G. BRAINE.
